COMBINED THERMOSTATIC CONTROL HOUSING AND SUPPORTING BRACKET

Edward G. Them, Mansfield, Ohio, assignor to Therm-O-Disc, Incorporated, Mansfield, Ohio, a corporation of Ohio

Filed July 17, 1964, Ser. No. 80,911

Term of patent 14 years

(Cl. D52—7)

FIG. 1

FIG. 2

FIG. 3

FIG. 4

FIG. 5

FIG. 6

FIGURE 1 is a front elevational view of a combined thermostatic control housing and supporting bracket embodying my new design;

FIGURE 2 is a side elevational view thereof;

FIGURE 3 is a top plan view thereof;

FIGURE 4 is a bottom view thereof;

FIGURE 5 is a perspective view showing portions of the front, side, and top thereof;

FIGURE 6 is a perspective view showing the backside and top thereof.

The undisclosed side of FIGURE 2 is substantially the same in appearance as the side shown.

I claim:

The ornamental design for a combined thermostatic

control housing and supporting bracket as shown and described.
